Filed Feb. 9, 1956, Ser. No. 564,529

6 Claims. (Cl. 187—1)

This invention relates generally to improved conveyorized machines for electroplating, and more particularly to such machines having supporting chassis, or lift frames mounted for vertical movement on a frame and adapted to convey workpieces through successive processing tanks.

The instant invention comprises improvements in plating machines of the general type described in U.S. Patent No. 2,479,322 and Re. 24,072. In this type of a machine a work-carrying frame structure generally called a chassis is alternately raised and lowered by means of chains trained over sprockets and pulled by one or more actuating elements such as hydraulic cylinders or electric motors. It is generally desirable to reduce the weight of the chassis in order to minimize the lifting power requirement. The rigidity of the chassis, therefore, is limited by this consideration and it has been found desirable to support the chassis at several points along its length to insure an even lifting movement thereof and to prevent binding of the chassis on its slide guides. As the length of the chassis is increased it becomes increasingly difficult to provide uniform support along its entire length. If a single actuating element is attached to the various support points by a plurality of chains of different lengths, the stretch characteristics of the chains become troublesome. The long chains tend to stretch more than the short chains and to permit portions of the chassis remote from the actuating element to sag and as the chassis is raised there is a tendency for the chassis to chatter or flutter. If, on the other hand, a plurality of actuating elements is employed it is difficult to synchronize these elements to insure an even and uniform lifting motion of the chassis.

Accordingly, one object of the instant invention is to improve chassis-type plating machines. Another object is to provide a chassis-type plating machine having lifting means which do not require chains of unequal lengths and which lift the chassis without binding or flutter. Still another object is to provide a chassis-type plating machine wherein the means for lifting the chassis automatically equalizes and coordinates the efforts of a plurality of actuating elements.

These and other objects are accomplished according to the instant invention which provides a chassis-type plating machine including a chassis lift mechanism comprising a rigid tension bar supported on the machine frame in a horizontal position above and parallel to the chassis for longitudinal reciprocating travel relative thereto. The tension bar is attached to the chassis at a plurality of points by flexible means and is driven longitudinally in a horizontal direction by actuating means such as a hydraulic cylinder or an electric motor. This horizontal motion is translated to the chassis through the flexible means to effect uniform lifting and lowering of the chassis. The invention also contemplates the use of pairs of such tension bars actuated reciprocally and linked together through equalizing means so that motion of one in one direction produces an exactly equal motion of the other in the opposite direction.

The invention will be described in greater detail in connection with the accompanying drawings of which:

view being a section through the upper frame channels and taken along the line 17—17 in Fig. 15.

Fig. 18 is a schematic elevational view illustrating the general arrangement of the chassis lift mechanism of the machine shown in Figs. 2A, 2B, and 2C; and

Fig. 19 is a schematic plan view of the lift mechanism illustrated in Fig. 18.

One embodiment of the instant invention as shown in Figs. 1 and 1A comprises a plating machine having a central frame including vertical columns 10 braced by lower longitudinal channels 11 and 12, diagonal bracing members 13 and upper longitudinal channels 14. An elongated chassis 16 of welded tubular construction is slidably mounted on the central frame and is provided with roller equipped guide brackets (not shown) which engage the vertical columns 10 for smooth vertical movement. A guide bracket such as the one shown in detail in Patent No. 2,479,322 may be used here. At the center of the machine a double column 18 supports a vertical hydraulic cylinder 20. A piston rod 22 projects from the lower end of the cylinder 20, the upper end of the cylinder 20 being secured to the upper channels 14. The lower end of the piston rod 22 is provided with a cross-head 24 received in vertical guides 26 secured to the column 18. Two pairs of chains 28 and 30 are secured to the crosshead 24, one pair at each side thereof, and extended vertically to be trained over the sprockets 31 mounted between the channels 14 near the top of the machine.

A pair of tension bars 32, which overlap at an intermediate portion of the machine, are slidably supported in brackets 33 attached to the upper channels 14. Racks 34 are secured to the tension bars along the overlapping portions thereof and mesh with pinion gears 36 which are mounted on fixed pivots between the two racks 34. Thus, the tension bars are geared together and movement of one tension bar in one direction causes the other tension bar to move in the opposite direction. One of the chains 28 is secured to the left-hand tension bar 32a, and one of the chains 30 is secured to the right-hand tension bar 32b. The other ones 28a and 30a of the two pairs of chains 28 and 30 are brought down over individual sprockets 40 to be secured to the chassis 16. Thus, when the piston crosshead 24 moves downwardly the tension bars 32 are drawn toward each other as indicated by the arrows 19.

Short lift chains 38 are secured to the chassis at spaced intervals along the length thereof. These lift chains 38 are extended upwardly over sprockets 40 attached to the frame and secured to the tension bars 32. When the tension bars are moved together toward each other, they pull on the lift chains to lift the chassis. Since all the chains 28, 30 and 38 are relatively short their stretching is minimized and, since they are all of substantially equal lengths, they all stretch in service by about the same amount. The chassis may, therefore, be raised and lowered evenly and uniformly along its length and without binding or flutter.

A second and preferred embodiment of the invention comprises a plating machine having separate tension and equalizer bars linked together and actuated by a plurality of hydraulic cylinders. This machine is illustrated in Figs. 2A, 2B, and 2C, which may be aligned end to end to show the complete machine. The machine is a relatively long one of the so-called return type and may be several hundred feet long. It has a central frame comprising two double, vertical columns 18, and eight single, vertical columns 10 spaced along and rigidly braced by opposed pairs of bottom longitudinal channels 11, middle longitudinal channels 12 and upper longitudinal channels 14. The lower and middle longitudinal channels 11 and 12, respectively, are further braced by diagonal bracing members, such as the members 13 shown in the drawing. The frame construction is generally similar to the frame of the machine shown in Fig. 1, except that it is longer

and includes more than one double column 18 adapted to support a hydraulic actuating cylinder. A chassis 16', of tubular metal frame work and generally similar to the chassis 16 heretofore described in connection with the machine illustrated in Fig. 1, is mounted on the columns 10 and 18 for vertical movement between the channels 12 and 14. An angle iron, work-supporting rail 17 is secured to the chassis 16', and workpieces slidably supported by hangers (not shown) on the rail 17 may be advanced around the machine by means of any convenient pusher rod mechanism such as the pusher rods 21.

The general principle of operation for raising and lowering the chassis 16' is illustrated schematically in Figs. 18 and 19, and reference should be made to these figures in conjunction with the following description.

When in its lowered position, the chassis 16' rests upon the frame of the machine and may be supported by the middle longitudinal channels 12. When it is raised, the chassis 16' is supported by a series of chains 28b, 30b,

20 38, 112 and 118 which are trained over sprockets and connected to various other parts of the machine, as described in detail hereinafter. The chassis-supporting chains 38 and 118 are connected between the chassis and a series of four tension bars 100-1, 100-2, 100-3, and 25 100-4 which are slidably supported on rollers 102 secured between the upper frame channels 14, as shown in Figs. 2, 3 and 13. Each of the tension bars 100 comprises a pair of parallel rods secured together at various points along their length by spacer members 103 and 104 (Figs. 30 6 and 7). The chassis lift chains 38 are attached to the ends of the respective tension bars by means of spacers 104 welded between the rods of the tension bars, as shown in Figs. 6 and 7. Other chassis lift chains 118 are connected at intermediate points along the length of 35 the tension bars in a similar manner to the chains 38, as shown in Fig. 3.

The tension bars are longitudinally actuatable by means of chains 28a, 28c, 30a and 30c attached to the ends of the tension bars remote from the chassis lift chains 38.

40 40 These actuating chains 28a, 28c, 30a and 30c are trained over sprockets 31 and are attached to the crossheads 24 of the actuating hydraulic cylinder assemblies 20. They connect the left-hand pair of tension bars 100-1 and 100-2 to the left-hand cylinder crosshead 24, and the 45 right-hand pair of tension bars 100-3 and 100-4 to the right-hand cylinder crosshead 24'.

Each of the hydraulic cylinders 20 is similar in construction and mounting details to the hydraulic cylinder 20 heretofore described in connection with the machine shown in Fig. 1. Each of the hydraulic cylinders 20 is mounted between the two posts of a double vertical column 18 of the machine and has an upper base plate 20a fixed to a bracket (not shown) secured between the channels 14. Each cylinder 20 includes a piston (not shown) to which is connected a piston rod 22. The piston rods 22 project from the lower ends of the cylinders and are provided with crossheads 24 and 24', which are received in vertical guides 26 secured to the columns 18. The actuating chains 28a, 28c, 30a and 30c are attached to the ends of the crossheads, as shown in Figs. 2A and 2C. Thus, when the hydraulic cylinders 20 are extended they draw the actuating chains 28a, 28c, 30a and 30c downwardly to draw together the separate pairs of tension bars 100-1 and 100-2, and 100-3 and 100-4,

55 65 the tension bar 100-1 being drawn toward the tension bar 100-2, and the tension bar 100-3 being drawn toward the tension bar 100-4. Additionally, supplemental chassis lift chains 28b and 30b are attached to the crossheads 24 and 24' and trained over the triple faced sprockets 31, and over the single sprockets 33 and attached at their far ends to the chassis 16'. Thus, when the hydraulic cylinders 20 are actuated, the crossheads 24 and 24' not only draw together the tension bars but also through the lift chains 28b and 30b directly lift the chassis 16'.

A counterweight 110 is provided in each of the single columns 10 at least partially to balance the weight of the chassis 16' and to minimize the lifting force required of the hydraulic cylinders 20. The counterweights 110 are connected to the chassis 16' by means of chassis lift chains 112 which are trained over sprockets 114 and 116 so that the counterweights 110 move down when the chassis 16' is raised. (The counterweights 110 are not indicated in Figs. 18 and 19.)

The tension bars 100-1 to 100-4 are tied together and their movements equalized with respect to each other by an equalizer assembly including a pair of equalizer bars 32a and 32b. The equalizer bars are I-beam members slidably supported upon rollers mounted in brackets 50 attached to the top of the upper, longitudinal frame channels 14. Details of the mounting brackets 50 and the roller supports for the equalizer bars 32a and 32b are shown in Figs 12 and 13. Each of the brackets 50 comprises a pair of short side channels 52, and a welded-on top channel 54. A small angle bracket 56 is welded or otherwise attached to the top channel 54. A shaft 58 is secured between the side channel 52 and the angle bracket 56 to support a pair of parallel, tapered rim roller wheels 60. The equalizer bars 32a and 32b are supported upon the roller wheels 60 and are braced against lateral movement by a pair of horizontal rollers 64 that roll against the web portion 66 of the equalizer bars 32. The horizontal rollers 64 are individually mounted upon forwardly extending bracket plates 62 which are secured to the side channels 52 of the brackets 50. Thus supported, the equalizer bars 32a and 32b are freely slideable longitudinally of the machine and are rigidly supported against lateral displacement.

Each of the equalizer bars 32a and 32b extends about half the length of the machine. They terminate at their overlapping ends in racks 70a and 70b, respectively, which are geared together through a pinion assembly 76 in much the same manner as the racks 34 heretofore described in connection with the machine shown in Fig. 1. As shown in Figs. 8 and 9, the racks 70 are supported upon rollers 74 mounted upon brackets 72 which are bolted or otherwise attached to the upper frame channels 14. The racks 70 face each other and extend through the pinion assembly 76 shown in greater detail in Figs. 15 and 17. The ends of the racks 70 remote from their respective equalizer bars extend beyond the gear box 76 and are attached to different ones of the tension bars 100-2 and 100-3 as described in greater detail herein-after.

Referring now to Figs. 15-17, the equalizer pinion assembly 76 comprises a lower gear plate 78, an upper gear plate 80 and upper and lower side spacers 82 all secured together by bolts 84. The box 76 rests upon mounting pads 87 and is secured to the upper frame channels 14 by stud bolts 86. A bearing mount bar 88 is secured between the upper and lower side spacers 82 on each side of the box. Three small horizontally disposed rollers 90 are mounted upon each of the bearing mount bars 88 and make contact with the outer surfaces of the racks 70a and 70b, respectively, to maintain the racks in mesh with the pinion gears 92. Four pinion gears 92, each supported by a shaft 94 and a bearing 96, and secured between the lower gear plate 78 and the upper gear plate 80, are mounted between the opposed racks 70a and 70b. Thus, movement of one equalizer bar a predetermined distance in one direction causes the opposite equalizer bar to move an exactly equal distance in the opposite direction.

The tension bars 100-1 to 100-4 are rigidly attached to the equalizer bars 32a and 32b and the racks 70a and 70b, as shown generally in Figs. 4A-4C and in detail in Figs. 6, 7, 10 and 11. The tension bars 100-1 and 100-3, that move toward the right as shown in the drawings when the hydraulic cylinders 20 are extended, are connected to the equalizer bar 32a and to the rack 70a,

respectively. The tension bars 100-2 and 100-4, that move toward the left as shown in the drawing when the hydraulic cylinders 20 are extended, are rigidly attached to the equalizer bar 32b and the rack 70b, respectively.

At the right-hand end of the machine the tension bar 100-4 is welded to a spacer plate 102 which is bolted to the bottom flange of the equalizer bar 32b. Near the center of the machine the tension bar 100-2 is connected to the rack 70b by means of an angle iron bracket 106 welded to the tension bar members and bolted to the rack. Correspondingly, tension bars 100-1 and 100-3 are similarly attached to the equalizer bar 32a and to the rack 70a, respectively. Illustrative structural details of these connections are shown in Figs. 10 and 11.

Thus, the tension bars are linked to each other through the equalizer assembly so that the tension bars 100-1 and 100-3 are forced to move together in one direction, and the tension bars 100-2 and 100-4 are forced to move together an equal distance in the opposite direction. Any difference or tendency toward a difference in the movement of or the force exerted by different ones of the hydraulic cylinders 20 is equalized and distributed throughout the chassis lift mechanism by the tension bar-equalizer bar combination. Moreover, the lift chains are relatively short and are all of substantially equal lengths so that the problem of differential stretch between the chains is minimized. The different lift points along the length of the chassis 16' are all lifted and lowered simultaneously and synchronously, thus preventing binding or flutter of the chassis.

It will be seen that any number of hydraulic cylinders such as the cylinders 20, electric motors or other actuating means may be utilized in connection with a lift mechanism according to this embodiment of the invention. Each hydraulic cylinder or actuating motor would be linked to one pair of tension bars which it draws together when energized. Each one of the tension bars would then be attached to one of the two equalizer bars depending upon its direction of movement when lifting the chassis 16'.

The use of reciprocating tension bars in combination with separate equalizer means provides symmetry to the structure and permits relatively simple alignment of the sprockets and the lift chains. Furthermore, if unbalanced forces are encountered, force from one tension bar is transmitted directly through an equalizer bar to another tension bar so that strains on the equalizer pinion gears are minimized.

What is claimed is:

1. Lift apparatus for an electroplating machine of the type having a frame and a chassis slidably mounted upon the frame for vertical travel relative thereto, said apparatus comprising a pair of horizontal tension bars mounted on the frame for horizontal travel relative thereto, a plurality of rotatable members pivoted upon the frame at longitudinally spaced points near the top thereof, a plurality of flexible members trained over said rotatable members and connected between spaced points along each of said tension bars and spaced points along the chassis, actuating means to move said tension bars horizontally with respect to the frame, and equalizing means comprising a pair of racks and a fixed point pinion gear meshed with both said racks, said racks being rigidly affixed to respective ones of said tension bars so that a predetermined travel of one of said tension bars in one direction produces an equal travel of the other one of said tension bars in the opposite direction.

2. Lift apparatus for an electroplating machine of the type having a frame and a chassis slidably mounted upon said frame for vertical travel relative thereto, said apparatus comprising a plurality of tension bars mounted upon the frame for horizontal travel relative thereto, a plurality of rotatable members pivoted upon the frame at longitudinally spaced points near the top thereof, a plurality of flexible members trained over said rotatable members and connected between spaced points along

each of said tension bars and spaced points along the chassis, fluid actuating means to move said tension bars horizontally with respect to said frame, a first means on each of said tension bars and second means cooperating with pairs of said first means for equalizing the travel 5 in opposite directions of said tension bars.

3. Lift apparatus for an electroplating machine of the type having a frame and a chassis mounted upon said frame for smoothly guided vertical travel relative thereto, said apparatus comprising a plurality of tension bars 10 slidably mounted upon the frame for horizontal travel relative thereto, a plurality of rotatable members pivoted upon the frame at longitudinally spaced points near the top thereof, a plurality of flexible members trained over said rotatable members and connected between spaced points along each of said tension bars and spaced points along the chassis, actuating means to move said tension bars horizontally with respect to said frame, and equalizing means comprising a pair of equalizer bars mounted upon said frame for horizontal longitudinal movement relative thereto, a pair of racks, and a fixed pivot pinion gear, each of said racks being rigidly connected to a different one of said equalizer bars, said racks engaging diametrically opposed portions of said pinion gear, and said equalizer bars being rigidly connected to selected ones of said tension bars.

4. An electroplating machine comprising a frame, a chassis mounted upon said frame for smoothly guided limited vertical travel relative thereto, a plurality of horizontal tension bars slidably mounted on said frame above the upper limit of travel of said chassis, a plurality of sprockets pivoted on said frame, a plurality of lift chains trained over said sprockets and connected between spaced points along said tension bars and spaced points along said chassis, one end of each of said chains being fixedly connected to one of said tension bars, the other end of each of said chains being fixedly connected to said chassis, said machine further comprising hydraulic cylinder means connected to said tension bars to produce horizontal travel of said tension bars when said hydraulic cylinder means are actuated, a pair of equalizer bars, a pair of racks, and a pinion gear, each of said equalizer bars being rigidly connected to different ones of said tension bars, each of said racks being rigidly connected to a different one of said equalizer bars, said racks 45 engaging diametrically opposed sides of said pinion gear, said pinion gear being rotatably mounted at a fixed point upon said frame.

5. An electroplating machine comprising in combina-

tion a frame, a chassis mounted on said frame for vertical movement relative to said frame, track means on said chassis for supporting work pieces and propelling means associated with said track means for moving work pieces along said track means, a plurality of pivot means mounted on said frame, a plurality of tension bars on said frame disposed parallel to the longitudinal axis of said chassis, a plurality of flexible members trained over said pivot means and attached to each of said tension bars and to said chassis at spaced points on each, a plurality of fluid actuatable power means mounted on said frame attached to said tension bars, and equalizing means comprising first means on each of said tension bars and second means cooperating with pairs of said first means for equalizing the travel in opposite directions of said tension bars.

6. An electroplating machine comprising in combination a chassis mounted on said frame for vertical movement relative to said frame, track means on said chassis 20 for supporting work pieces and propelling means associated with said track means for moving work pieces along said track means, a plurality of pivot means mounted on said frame, a plurality of tension bars on said frame disposed parallel to the longitudinal axis of said chassis, a plurality of flexible members trained over said pivot means and attached to each of said tension bars and to said chassis at spaced points on each, a plurality of power means mounted on said frame attached to said tension bars, and equalizing means associated with said tension bars causing one tension bar to move a predetermined distance in one direction when another tension bar moves a predetermined distance in the opposite direction, said equalizing means comprising at least one pair of equalizer bars, said equalizer bars being rigidly connected to selected ones of said tension bars, a pair of racks and a pinion gear, each of said racks being rigidly connected to a different one of said equalizer bars, and said racks engaging diametrically opposed portions of said pinion gear.
